US0D1019733S

(12) **United States Design Patent** (10) **Patent No.:** **US D1,019,733 S**
(45) **Date of Patent:** **** Mar. 26, 2024**

(54) **CAMERA**

(71) Applicant: **HANWHA TECHWIN CO., LTD.**,
Seongnam-si (KR)

(72) Inventor: **Ho Jin Park**, Seongnam-si (KR)

(73) Assignee: **HANWHA VISION CO., LTD.**,
Seongnam-si (KR)

(**) Term: **15 Years**

(21) Appl. No.: **29/840,034**

(22) Filed: **May 25, 2022**

(30) **Foreign Application Priority Data**

Dec. 13, 2021 (KR) 30-2021-0059967

(57) **CLAIM**

The ornamental design for a camera, as shown and described.

DESCRIPTION

FIG. 1 is a perspective view of a camera, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof.

The broken lines in the drawings form no part of the claimed design.

1 Claim, 7 Drawing Sheets
